DESIGN FOR A BELT

Constance L. Brae, New York, N. Y.

Application June 22, 1942, Serial No. 107,297

Term of patent 3½ years

To all whom it may concern:

Be it known that I, Constance L. Brae, a citizen of the United States residing at 310 W. 99th Street, city of New York, county of New York, and State of New York, have invented a new, original, and ornamental Design for a Belt, for which the following is a specification, reference being had to the accompanying drawing, forming part thereof.

Fig. 1 is a fragmentary view, of one end of a belt showing my new design,

Fig. 2 is a plan view of the belt on a smaller scale, and

Fig. 3 is a perspective view of the belt shown in Fig. 2 in buckled position.

I claim:

The ornamental design for a belt, as shown.

CONSTANCE L. BRAE.
